UNITED STATES PATENT OFFICE.

JOHN N. PETERSEN AND WILLIAM F. PETTIT, OF NEW ORLEANS, LOUISIANA.

CARBURETER.

976,911.

Specification of Letters Patent. Patented Nov. 29, 1910.

Application filed November 14, 1908. Serial No. 462,583.

To all whom it may concern:

Be it known that we, JOHN N. PETERSEN and WILLIAM F. PETTIT, citizens of the United States, and residents of the city of 5 New Orleans, in the parish of Orleans and State of Louisiana, have invented a new and Improved Carbureter, of which the following is a full, clear, and exact description.

This invention relates to carbureters for 10 use in connection with gasolene engines.

One object of the invention is to provide a carbureter having a cup-shaped mixture valve, having a double flat seat whereby the air and gasolene are shut off simultaneously, 15 making it ideal for two-cycle engines, as no other check valve is needed.

A further object is to provide a carbureter in which the gasolene is spread out as it comes in contact with the under side of 20 the mixture valve and is then passed through a series of compartments, where it mixes with the air, and the whole mixture is united in one volume before passing into the engine.

25 A further object is to provide novel means for regulating the air and gasolene in correct proportions to each other, and varying the proportions to suit the requirement of any particular engine.

30 The invention consists in the construction and combination of parts, to be more fully described hereinafter and particularly set forth in the claims.

Reference is to be had to the drawings 35 forming a part of this specification, in which similar characters of reference indicate corresponding parts in all the figures, and in which—

Figure 1 is a central vertical section 40 through the carbureter, showing a straight connection at the top of the same; Fig. 2 is a central vertical section, taken at right angles to the section in Fig. 1, and showing the means for holding the air valve cup in 45 position; Fig. 3 is a horizontal section, taken on the line 3—3 in Fig. 2; Fig. 4 is a horizontal section, taken on the line 4—4 in Fig. 1; Fig. 5 is a section taken on the line 5—5 in Fig. 1; and Fig. 6 is a side elevation, 50 partly in section, of the carbureter, showing an angle connection at its upper end.

In said drawings, the body or valve casting 1 of the carbureter has an internal annular flange 2, about midway of its length, 55 which is finished with a flat valve seat 3. The body of the carbureter is thereby divid-

ed into an upper chamber 5 and a lower chamber 6. Extending longitudinally in the interior of the carbureter body 1 are a plurality of longitudinal flanges 8 extending from the 60 annular flange 2 upward to the top of said body and having at their bottoms where they join the annular flange 2, curved or flaring portions, as shown in Fig. 2. Said longitudinal flanges 8 are finished on their 65 inner faces to fit the exterior of a mixture valve 9.

The mixture valve 9 comprises a cup having a flat bottom 10, adapted to rest upon the seat 3, said cup being provided with a 70 plurality of drip holes 12 extending diagonally through the lower corner of the valve, which enables any crude oil or water which may become condensed therein to drain away. Bearing against the bottom 10 is a 75 spiral spring 14, said spring bearing at its upper end against the inside of a coupling 15, and lying within a notch 16 provided therefor in said coupling.

It will be seen that the longitudinal 80 flanges 8, in connection with the mixture valve 9, divide the upper chamber 5 into four compartments 18. The number of the compartments may obviously be varied by varying the number of longitudinal flanges. 85

Extending across the inside of the body 1 is a web 20, having a central boss 21 at its upper side, the upper surface of which is in line with the valve seat 3, and is therefore adapted to come in contact with the 90 under side of the bottom 10 of the mixture valve 9. Said web is provided with a central vertical passage 22, which connects with a longitudinal passage 24, which is threaded for a portion of its length to receive the 95 threaded stem 25 of the needle valve 26. Extending in line with the passage 24 is a passage 28, which is enlarged into a screw-threaded opening 29 for the reception of the gasolene supply pipe 30. A wall 31 extends 100 between the passages 28 and 24, and is provided with a conical passage 32 for the reception of the end of the needle valve 26.

The body 1 is provided with a screw-threaded recess 35, adapted to receive a 105 gland 36, which retains a packing washer 37, thereby forming a stuffing box around the stem of the needle valve 26. The outer end of the needle valve stem is formed into a pinion 40, having teeth 41, adapted to mesh 110 with teeth 42 on a sector 43, which is slidably mounted in a slot 44 of the handle 45

- of an air valve 46. The sector 43 is screw-threaded at its lower end 47, to co-act with a thumb nut 48, by which it may be firmly clamped in position in the handle 45.
- 5 In the periphery of the body 1, near its lower end, are a plurality of elongated holes or ports 50, adapted to register with similar holes or ports 51, formed in the periphery of the vertical sides of the air valve 46.
- 10 The air valve 46 is held in rotatable relation with the lower end of the body 1 by means of two spring wires 52, having horizontal arms extending through apertures 53 formed in the body 1. The wires 52 are bent at 15 right angles, and their vertical arms are brought into juxtaposition, and screw-threaded to co-act with a thumb nut 54. The two vertical stems of the wires 52 pass through a central hole 56 in the bottom of the air valve 46, said hole having two lateral recesses 57 communicating therewith. These recesses 57 are adapted to receive 20 small projections 58 formed on the upper side of the thumb nut 54, to prevent the nut 54 from rattling loose through the vibrations caused by the engine. By tightening the nut 54, the degree of pressure with 25 which the air valve 46 is maintained against the body 1 may be varied to prevent the valve changing its position on account of the vibrations of the engine. By grasping the handle 45, the air valve 46 may be rotated about the lower end of the body 1, the thumb-nut 54 rotating therewith about 30 the threaded ends of the wires 52, since the projections 58 on said nut lie within the recesses 57 and thereby prevent the relative rotation of said nut and air valve, except 35 when the nut is turned manually. It is 40 only necessary to turn said handle for a portion of a revolution in order to bring the ports 50 and 51 into full registry. The wires 52, being retained in the apertures 53 in the body 1, support said air valve.
- 45 In Fig. 1, we have shown a coupling 15, which is screw-threaded to the upper end of the carbureter body, and adapted to receive a pipe 17, having straight connection, and in Fig. 6, we have shown an angle connection 60, which is screw-threaded to the upper end of the carbureter body 1, to 50 merely show the varieties of connections which may be fastened to the carbureter.
- The operation of the device is as follows:—The sector 43, when in its innermost position will cause the rotation of the needle valve 26 through co-operation with the pinion 40 for only about a half turn, thus allowing a small amount of gasoline to 55 pass into the carbureter through the central passage 22. By moving the sector 43 along the handle 45, the extent to which the needle valve 26 will be opened may be varied. When the sector is in its outermost position, the needle valve will be given a full turn, 60

when the pinion 40 traverses the entire length of the rack upon the upper side of the sector. It will be noted that the proportions of air and gasoline may be very accurately adjusted and this adjustment 70 maintained throughout the running of the engine.

By varying the location of the sector-rack 43 along the handle 45, the extent of the arc traversed by the pinion 41 will be varied 75 accordingly, depending upon the distance of said rack from its center of rotation, and also the extent to which the handle 45 is rotated. The angular movement of the handle 45 is the same for any given opening of the air-valve, but the length of the arc traversed by the pinion 41 over the rack 43 will vary according to the distance of said rack from the center of rotation. Thus, any proportion of air and gasoline 85 may be supplied.

By the construction and arrangement shown, the proportion of air and gasoline is mechanically varied to be correct at all speeds. This variation of proportion is 90 predetermined by two adjustments. In adjusting the carbureter the sector-rack 43 is removed from the handle, and the needle valve and the air valve are set until the highest speed is attained and the positions 95 of the valves are noted. Both valves are then shut down until the slowest speed is attained, and the rack is then secured at such point on the handle as will give the required travel of the needle valve between the extremes of high and low speed. The adjustment is then correct for all speeds and is 100 permanent.

The gasoline coming from the passage 22 comes in contact with the under side of the mixture valve 9, and is thereby spread out in all directions, and passing between the mixture valve 9 and its seat enters the compartments 18. The air coming in from the bottom of the body of the carbureter passes 105 around the web 20 and between the mixture valve and its seat, and also enters the compartments 18, thereby thoroughly mixing with the gasoline. During the compression 110 of the gases in the engine, or if for any other reason excessive back pressure should occur, the valve 9 will bear simultaneously against the seats 3 and 21, thereby simultaneously 115 shutting off the air supply and the gasoline supply. This obviates the use of an additional check valve. After the mixture rises 120 above the top of the mixture valve 9, it unites to form one volume and then passes to the engine.

Having thus described our invention, we 125 claim as new and desire to secure by Letters Patent:—

1. A carbureter comprising a valve casing having a substantially straight air passage therethrough, means for supplying gasoline 130

to said valve casing, means for supplying air thereto, a plurality of longitudinal flanges in said valve casing, means for controlling the supply of air and gasoline to said valve 5 casing, a mixture valve mounted to slide in said valve casing and having its periphery in contact with the inner faces of said longitudinal flanges, and two valve seats to which the gasoline supply and the air supply respectively lead, the said seats being arranged to be simultaneously engaged by said mixture valve, to check the flow of air and gasoline.

2. A carbureter, comprising a valve casing having a central passage for the supply of gasoline thereto and apertures for admitting air thereto, a valve for controlling the supply of gasoline to said passage, an elongated pinion on the stem of said valve, a 10 cap rotatably mounted at the end of said valve casing and having apertures for admitting air, which coöperate with the apertures in said valve casing, a handle on said cap provided with a radial slot, a rack co- 15 operating with said pinion mounted to slide on said handle and guided by said slot, and means whereby said rack may be secured in 20 adjusted position.

3. A carbureter, comprising a valve casing having a central passage for the supply of gasoline thereto and apertures for admitting air thereto, a valve for controlling the supply of gasoline to said passage, an elongated pinion on the stem of said valve, a cap 25 rotatably mounted at the end of said valve casing and having apertures coöperating with the apertures in said valve casing, for admitting air, a handle on said cap provided with a radial slot, a sector-shaped rack 30 meshing with said pinion and mounted to slide on said handle while guided by said slot, means for securing said rack in 35 adjusted position, and means for holding the said cap in rotatable relation with the end 40 of said valve casing.

4. A carbureter, comprising a valve casing having means for supplying gasoline thereto and apertures for admitting air thereto, a cap rotatably mounted on said valve casing, having apertures adapted to co-act with the apertures in said valve casing, and a 50 central hole with communicating recesses, a pair of wires supported in said body and projecting through said hole, and a nut on 55 said wires engaging the outside of said cap and having lugs adapted to enter said recesses.

5. A carbureter comprising a valve casing having means for supplying gasoline thereto, and apertures for admitting air thereto, a cap rotatably mounted on said 60 casing and having apertures adapted to register with the apertures in the valve casing, the said cap having a central hole in its bottom, a pair of spring wires having hori-

zontal arms extending through apertures in the valve casing, and vertical arms brought together and screw threaded, the said vertical arms extending through the hole in the bottom of the cap, and a nut on said threaded arms and engaging the outside of said cap.

6. A carbureter, comprising a hollow body forming a valve casing, a needle valve for controlling the supply of gasoline to said 70 valve casing, an elongated pinion on the stem of said valve, an air valve for supplying air to said valve casing, a handle on said air valve, a rack adjustable on said handle and along the elongated pinion and 75 engaging the latter, and means for fastening said rack to the handle at a point where the movement of the latter will give the required travel of the needle valve between the extremes of high and low speed.

7. A carbureter, comprising a valve casing having apertures for admitting air thereto, a needle valve for controlling the supply of gasoline to said valve casing, an elongated pinion on the stem of said valve, a cap 90 rotatably mounted at the end of said valve casing and having apertures for admitting air, the said apertures coöperating with the apertures in said valve casing, a handle on 95 said cap, and a rack coöperating with said pinion and adjustable on said handle to a predetermined position relative to said pinion, and means for securing said rack in the predetermined position.

8. A carbureter comprising a valve casing, having a passage for the supply of gasoline thereto, and apertures for admitting air thereto, a needle valve for controlling the supply of gasoline to said passage, and having a stem projecting from the said 100 valve casing, an elongated pinion on the projecting end of the valve stem, a cap rotatably mounted at the end of the valve casing and having apertures for admitting air the said apertures coöperating with the apertures in the valve casing, a handle projecting from the cap and extending below the 110 said elongated pinion, the handle being provided with an elongated slot, a sector-shaped rack meshing with the under side of said pinion at a predetermined point, and having a depending member secured in said slot in the handle, and means for holding the cap in rotatable relation with the end of the 115 valve casing.

9. A carbureter comprising a hollow body having an internal annular flange forming a valve seat and dividing the body into an upper and a lower chamber, a plurality of longitudinal flanges on the wall of said upper chamber, a mixture valve mounted to slide in said upper chamber and having its periphery in contact with the inner faces of said longitudinal flanges, the said flanges and mixture valve dividing the upper chamber 125 130

ber into a plurality of compartments, a central flat valve seat, a gasoline supply leading to said central valve seat, and means for admitting air to the lower chamber, the said mixture valve co-operating with said valve seats and the gasoline and air when the mixture valve is lifted passing between the said mixture valve and the annular valve seat to said compartments.

In witness whereof we have signed our names to this specification in the presence of two subscribing witnesses.
